(57) **CLAIM**

The ornamental design for a electrical connector housing, as shown and described herein.

DESCRIPTION

FIG. 1 is a front side elevational view of our electrical connector housing design for a first embodiment.

FIG. 2 is a back side elevational view of our electrical connector housing, showing our new design, for the embodiment in FIG. 1.

FIG. 3 is a right side elevational view of our electrical connector housing, showing our new design, for the embodiment in FIG. 1.

FIG. 4 is a left side elevational view of our electrical connector housing, showing our new design, for the embodiment in FIG. 1.

FIG. 5 is a perspective view of our electrical connector housing, showing our new design, for the embodiment in FIG. 1.

FIG. 6 is a plan (top) view of our electrical connector housing, showing our new design, for the embodiment in FIG. 1.

FIG. 7 is a bottom elevational view of our electrical connector housing, showing our new design, for the embodiment in FIG. 1.

FIG. 8 is a front side elevational view of our electrical connector housing, showing our new design, for a second embodiment.

FIG. 9 is a back side elevational view of our electrical connector housing, showing our new design, for the embodiment in FIG. 8.

FIG. 10 is a right side elevational view of our electrical connector housing, showing our new design, for the embodiment in FIG. 8.

FIG. 11 is a left side elevational view of our electrical connector housing, showing our new design, for the embodiment in FIG. 8.

FIG. 12 is a perspective view of our electrical connector housing, showing our new design, for the embodiment in FIG. 8.

FIG. 13 is a plan (top) view of our electrical connector housing, showing our new design, for the embodiment in FIG. 8; and,

FIG. 14 is a bottom elevational view of our electrical connector housing, showing our new design, for the embodiment in FIG. 8.

The broken line portion of the figure drawings is included to show portions of the article that form no part of the claimed design.
